UNITED STATES PATENT OFFICE

2,559,086

DEVICE FOR ADMINISTERING ENEMATA

George E. McLaren, Denver, Colo.

Application May 9, 1949, Serial No. 92,227

4 Claims. (Cl. 128—245)

1

This invention relates to improvements in devices for administering enemata.

Certain patients, to whom it is necessary to give enemata, have a weak sphincter muscle of the anus, or have no control thereof, whatever, by reason of certain types of paralysis or other causes. In these cases the well known manner of giving an enema with a catheter which projects into the rectum is unsatisfactory since the patient is unable to retain the injected fluid. Devices have been proposed for use with such patients, such as that shown by the patent to Lamson, 2,457,244, granted December 28, 1948, in which an inflatable seal is provided in the rectum above the sphincter muscle. Other devices which have been proposed for this general class of use are shown by the patent to Quimby, 862,507 granted August 6, 1907, and the patent to Stratton 1,137,242 granted April 15, 1915. It is to devices of the above identified type that the present invention more particularly relates.

One of the principal objects of the invention is to provide a seal device which engages the exterior portions of the anatomy, around the anus, in a novel and more advantageous manner.

Another object is to provide a device of the foregoing type through which a flexible tube may be inserted to any desired distance into the rectum or colon.

A further object is to construct such device of transparent material which aids in properly applying the device to the anatomy.

Further objects, advantages, and salient features will become more apparent from a consideration of the description to follow, the appended claims, and the accompanying drawing, in which:

Figure 1 is a top plan of the seal block which constitutes the subject of the invention;

Figure 2 is a side elevation thereof taken on line 2—2, Figure 1;

Figure 3 is an end elevation taken on line 3—3, Figure 2;

Figure 4 is an end elevation taken on line 4—4, Figure 2;

Figure 5 is a section taken on line 5—5, Figure 2 showing a portion of a hose employed with the seal block above referred to;

Figure 6 is a section taken on line 6—6, Figure 1; and

Figure 7 is a bottom plan taken on line 7—7, Figure 2.

Referring in detail to the drawing, the block 10 which forms the seal has an upwardly convex surface 11, in its longitudinal direction as best shown in Figures 2 and 6, which surface is gen-

2

erally convex also in its transverse direction as best shown in Figure 5. A slight ogee curve 12, on each side will usually be preferred. In the longitudinal direction, the upwardly convex surface 11 changes to concave surfaces 13, 14, at each end thereof. The surface again turns upwardly at 15, adjacent concave surface 13, at the left end (Figures 2 and 6), and similarly turns upwardly at 16, adjacent surface 14, at the right end. A circular aperture 17 extends through the block, from top to bottom, this aperture being substantially at the central transverse axis of the block, the upper end thereof extending through the generally central portion of surface 11. The aperture may be slightly curved, as shown in Figure 6, to form a curve which is a general curved continuation of the curve of the rectum.

For an average size adult the block may be approximately four inches in length and two inches in width, constructed of a transparent plastic material. The exact shape of the various curves is illustrative only and may be varied to fit the anatomy of the particular individual. Where precise fitting is required, as where the shape of the patient's anatomy may depart from what might roughly be termed "average" and to which an "average" shape would not properly conform, an impression is made of the anatomy with any suitable impression material, such as wax or the like, and a mould is then made from this impression. A hardenable liquid plastic is then poured into this mould, a suitable core such as a piece of rubber being employed therein to form the aperture 17. After hardening, the device is ready for use. If a patient is to be confined for any length of time and requires frequent enemata, it will usually be preferred to construct a block to the exact shape of the anatomy in the manner above described. This not only ensures the most exact fit, but by reason of the patient having a block for his individual use, it entirely eliminates any possibility of transmission of communicable diseases from one patient to another. The block may, of course, be sterilized by boiling, if desired. In the use of the device the patient is placed in a convenient position, such as on the side of his body, and the nurse or other attendant places the block between the buttocks with the upper convex portion 11 abutting the anus. It will be noted that the surface at 16 is somewhat lower than that at 15, the surface 16 abutting the anatomy substantially over the coccyx, and the surface 15 abutting the perineum. Since the anatomy over the coccyx is relatively hard and rigid, the surfaces between

14 and 15 may be firmly pressed against this region without discomfort to the patient and at the same time provide a support so that the block does not slip or move from its desired position. The block may be flat or any other shape at the bottom side and if desired any sort of finger engaging portions may be employed, such as cut out ends 18 which may receive the tips of the fingers of the attendant. These may be ribbed or roughened as desired.

Before the block is positioned against the anatomy, as above described, a rubber or other flexible hose 19 is inserted into the aperture 17 and fed therethrough to any desired distance which it is to extend into the rectum or colon. This hose must, of course, fit the aperture sufficiently snug to prevent leakage of fluid through the aperture around the outer surface of the hose. The length of the extending portion may then be adjusted as desired. Fluid is then injected in any well known manner and will be retained as long as the block is maintained against the anatomy. The fluid, of course, may be any of the various enemata such as cleansing, nutritive and many others.

While the material has been described as a plastic material it will be apparent that any other suitable material may be employed.

Having described the invention what I claim as new is:

1. A device for assisting in administering enemata, comprising; an elongated seal block having an oblong mound-like central portion of a shape to conform to the shape of the anus and a strip area of the anatomy immediately thereabout, upwardly extending portions at each end of the mound-like portion, one being constructed to conform to the anatomy covering the coccyx and the other conforming to the shape of the perineum, and an aperture extending through the seal block transversely to the longitudinal axis thereof having a portion in alignment with the anal opening.

2. A device in accordance with claim 1 including a hose of a size adapted to be threaded through the aperture to a desired distance beyond the anal opening, the outer wall of the hose being in fluid sealing engagement with the wall of the aperture.

3. A device in accordance with claim 1 wherein the seal block is constructed of transparent material, whereby its position against the anatomy may be observed.

4. A device for assisting in administering enemata, comprising; an elongated seal block having an oblong mound-like portion of a shape to conform to the shape of the anus and a strip area of the anatomy thereabout, an upwardly extending portion at one end of the mound-like portion shaped to conform to the anatomy covering the coccyx, an aperture extending through the seal block transversely to the longitudinal axis thereof having a portion in alignment with the anal opening, and a flexible hose of a size adapted to be threaded through the opening to a desired distance beyond the anal opening and into the rectum, the outer wall of the hose being in fluid sealing engagement with the wall of the aperture.
